UNITED STATES PATENT OFFICE.

JOHN S. MOAD, OF DALLAS, TEXAS.

SILO.

1,164,843.

Specification of Letters Patent. Patented Dec. 21, 1915.

Application filed November 28, 1913. Serial No. 803,610.

To all whom it may concern:

Be it known that I, JOHN S. MOAD, a citizen of the United States, residing at Dallas, in the county of Dallas and State of Texas, have invented certain new and useful Improvements in Silos, of which the following is a specification.

My invention relates to new and useful improvements in silos. Its object is to provide a silo of the interlocking cement stave type that will be absolutely air-tight and water-tight and will preserve silage perfectly under all weather conditions.

Another object is to provide an improved method of fastening the hoops upon a cement stave silo.

A further object is to provide a silo having a series of doors continuously extending from its top to its bottom, improved fastening devices being correlated with said doors.

Finally, a still further object of the invention is to provide a device of the character described that will be strong, durable, efficient and simple, and comparatively inexpensive to produce, and also one in which the several parts will not be likely to get out of working order.

With the above and other objects in view, the invention has relation to certain novel features of construction and operation, an example of which is described in the following specification and illustrated in the accompanying drawings, wherein:

Figure 1 is a view in front elevation of a silo, in which are embodied the novel features constituting my invention. Fig. 2 is a rear view of the same. Fig. 3 is a transverse sectional view, the section being taken upon the line *v*—*v* of Fig. 1. Figs. 4 and 5 are respectively a top and front view of a joint serving to connect the extremities of the hoops which hold the silo wall in place. Fig. 6 is a detail front view of one of the silo doors, showing also the portion of the silo forming a frame for said door. Fig. 7 is a horizontal sectional view, the section being taken upon the line *w*—*w* of Fig. 6. Fig. 8 is a horizontal sectional view taken upon the line *x*—*x* of Fig. 6. Fig. 9 is a vertical sectional view, the section being taken upon the line *y*—*y* of Fig. 6.

Referring now more particularly to the drawings, wherein like reference characters designate similar parts in all the figures, the numeral 1 denotes an annular cement member partially embedded in the ground, to

serve as a foundation for my silo. The cylindrical silo wall which rests upon the foundation 1 is comprised of rectangular cement staves 2 forming tiers, the horizontal joints of each tier, being staggered with relation to those of the adjacent tiers. The interlocking tongue and groove joints between each stave and the adjacent staves of the same tier are indicated at 3, similar joints 4 being formed between abutting lateral edges of the staves. The cement floor of the silo, which is designated by the numeral 5, is supported at its edges by the foundation 1.

At one side of the silo, there is provided a vertical series of doors 6, extending the full height of the silo and preferably formed of wood. In each of the staves 7 between which the doors 6 are fitted, there is embedded a reinforcing steel rod 8, forming an obtuse angle, the apex of which projects slightly from the stave intermediate of its ends.

Between each two adjacent doors 6, 80 there is interposed a combined sill and lintel 9, which has its extremities supported by the staves 7 adjacent to the door beneath said lintel, the staves being formed with cut-away corners to receive the lintels. In the 85 cement comprising each member 9, there are embedded two horizontal reinforcing rods 10, one above the other extending substantially the full length of the sill and formed at their extremities with eyes 11 in grooves 90 12 vertically extended across the sill ends. The eyes 11 of the upper and lower rods 10 of each sill respectively receive the lower extremities of the reinforcing rods 8 just above said sill and the upper extremities of the 95 rods 8 just below the sill. Each door 6 is mounted in the rear portion of the door aperture and has its lateral edges abutting forwardly against vertical shoulders 13 formed in the members 7, and its lower edge 100 abutting against a horizontal shoulder 13^a in the correlated sill. Through the center of each door there is transversely passed a bolt 15 carrying a sleeve 16 in front of the door and a latch arm 17 in front of said sleeve. When said latch arm is displaced to a horizontal position its extremities will project slightly beyond the lateral edges of the door, overlapping the staves 7 and restricting the door against rearward displacement. The latch arms 17 may be clamped 105 in their horizontal positions by handled

clamping nuts 18 mounted upon the front ends of the bolts 15. Upon the end portions of each door there are respectively mounted forwardly projecting arched brackets 19 5 which may serve both as door handles and as ladder rungs.

The silo walls are held to their cylindrical shape by two alternating series of hoops respectively designated by the numerals 20 10 and 21, and preferably having the nature of steel bands. Each of the hoops 20 is contiguous with one of the members 9, the outer faces of said members being grooved as indicated at 22 to receive said hoops. The 15 hoops 20 are each formed in two halves the joints being vertically alined at each side of the silo. These joints will preferably be formed by passing the end portions of a hoop through small brackets 23 and subsequently bending over the hoop ends, preventing removal of the brackets from the 20 hoop. Through the two brackets is passed a bolt 24, permitting considerable force to be exerted in tightening the hoop upon the 25 silo. The hoops 21 are disposed midway between the hoops 20, and are also formed in two halves, which are joined together at the rear of the silo in the manner already described. At the front of the silo, the other 30 extremities of the halves of each hoop are respectively engaged with the projecting portions of two opposite members 8. Thus it is seen that the hoops are so arranged as to avoid obstructing the door apertures in 35 any way. The roof 25 is preferably made of sheet-metal and has the form of a cone of gradual inclination.

The disposition of the hoops 20 and 21 is such that said hoops together cover all of 40 the horizontal joints between the staves, each stave thus being engaged by hoops at both ends and at the middle, producing a very strong structure. To have access to the silo by any of its door apertures it is necessary 45 only to loosen the clamping nut 18, turn the

correlated bar 17 through a slight angle, and displace the door into the silo from the door aperture. The reinforced construction of the staves 7 and members 9 adequately compensates for the reduction of strength in the 50 front portion of the silo wall resulting from the presence of the door apertures.

The invention is presented as including all such modifications and changes as properly come within the scope of the following 55 claims.

What I claim is:

1. In a device of the character described two door jambs, each of said jambs consisting of a plurality of sections, cross braces 60 between the two jambs, rods traversing said cross braces and projecting therefrom, the projecting ends being formed into loops, a rod traversing each of said jamb sections and projecting therefrom, all arranged so 65 that the projecting portions of each rod traversing a door jamb section traverse said loops projecting from said cross braces.

2. In a device of the character described two door jambs, each of said jambs consisting of a plurality of sections, cross braces between the two jambs, rods traversing said cross braces and projecting therefrom, the projecting ends being formed into loops, a rod traversing each of said jamb sections 70 and projecting therefrom, all arranged so that the projecting portions of each rod traversing a door jamb section traverse said loops projecting from said cross braces, in combination with adjustable tie bands 75 circling the body of the silo, said bands traversing the cross braces and embedded therein.

In testimony whereof I have signed my name to this specification in the presence of 80 two subscribing witnesses.

JOHN S. MOAD.
